UNITED STATES PATENT OFFICE

129,867

DESIGN FOR A PORTABLE OIL FILTERING UNIT

Russell P. Dunmire, Alliance, Ohio, assignor to
The Buckeye Laboratories, Inc., a corporation
of Ohio

Application April 16, 1941, Serial No. 100,416

Term of patent 14 years

To all whom it may concern:

Be it known that I, Russell P. Dunmire, a citizen of the United States, residing in the city of Alliance, county of Stark, and State of Ohio, have invented a new, original, and ornamental Design for a Portable Oil Filtering Unit, of which the following is a specification, reference being had to the accompanying drawings, forming a part thereof.

Figure 1 is a rear side elevational view of a portable oil filtering unit, showing my new design;

Figure 2 is an end elevational view looking from right to left in Figure 1;

Figure 3 is a front elevational view, thereof: and

Figure 4 is an end elevational view looking from right to left in Figure 3.

The dominant features of the design reside in the portions shown in full lines.

I claim:

The ornamental design for a portable oil filtering unit, substantially as shown and described.

RUSSELL P. DUNMIRE.
